UNITED STATES PATENT OFFICE

JOHN S. STOKES, OF HUNTINGDON VALLEY, PENNSYLVANIA, ASSIGNOR TO STOKES AND SMITH COMPANY, OF PHILADELPHIA, PENNSYLVANIA, A CORPORATION OF PENNSYLVANIA

METHOD OF WRAPPING STAYED BOXES

Application filed September 4, 1928. Serial No. 303,688.

My invention relates to the formation of stayed boxes, cartons, containers, or the like, hereinafter generically termed "boxes".

In accordance with my invention, tabs are adhesively secured to a box, particularly an unshaped box, or box-blank, and substantially immediately thereafter, or simultaneously, before material setting of the adhesive on the tabs, a wrapper, preferably 5 coated with adhesive, is applied to the box, the adhesive coatings on the tabs and wrapper being fluid during wrapping of the box; more specifically, the tabs after being coated with adhesive are applied to a corner-cut 10 box-blank, particularly a one-piece blank, and the tabbed wrapper is transported to a wrapping station, at which, during a wrapping operation, the blank is simultaneously shaped and wrapped before setting of the 15 adhesive.

My invention resides in the methods hereinafter described and claimed.

For an illustration of some of the various methods of practicing my invention, reference is to be had to the accompanying drawings in which, in perspective:

Fig. 1 represents a stack of box blanks.

Fig. 2 illustrates a single box blank to which tabs have been adhesively attached.

Fig. 3 depicts the blank of Fig. 2 after a shaping operation.

Fig. 4 represents a stack of wrappers.

Fig. 5 illustrates a single wrapper to which a coating of adhesive has been applied.

Fig. 6 is a view of the shaped box blank of Fig. 3 in registering relation with a wrapper.

Fig. 6a illustrates a modified step of my invention in which the unshaped box of Fig. 2 is in registering relation with a wrapper.

Figs. 7 to 9, inclusive, represent subsequent successive stages of the box wrapping operation.

Figs. 10 to 12, inclusive, are modified forms of tabbed box blanks.

Referring to the drawings, to the individual box blanks B, after their removal from the stack S, or while an end blank of 50 the stack, are adhesively secured the tabs T.

Preferably coatings of adhesive are applied to the tabs and the coated tabs are thereafter applied to the wrapper engaging surface of a box blank; alternatively, adhesive may be applied to the box blank; for example, locally in dabs as applied by a suitable stencil, and thereafter the tabs brought into contact therewith.

Although as shown, box blank B is a single piece of cardboard or equivalent, it may 55 be a composite blank, made of several component parts of suitable size, shape and material, as disclosed in my co-pending application Serial No. 88,231, filed February 15, 1926.

The side walls s and end walls e of blank B are bent into box-simulating position and the free or projecting portions of the tabs T are wiped or pressed into engagement with walls adjacent to those to which they are 60 attached to reinforce the corners formed by the abutting walls. As shown, the tabs are applied to the side walls s and during the shaping operation engage the end walls e 65 ultimately as hereinafter described to reinforce the corners of the box. It is within the scope of my invention to apply the tabs T to the end walls e and thereafter to effect their engagement with side walls s.

As an alternative, the side walls s and end walls e may be bent into box-forming position and thereafter the tabs adhesively applied in any sequence or simultaneously to the corners of the box thus formed. The individual tabs may engage the box walls in 70 any sequence or simultaneously. The shaped, tabbed boxes of Fig. 3, produced in any of the modes indicated, are brought in succession into registering relation with wrappers W, as at a wrapping station.

The wrappers W are or may be individual, corner-cut wrappers disposed in a stack S1 from which they may be moved and transported to the wrapping station. To the box-engaging surface of the successive end sheets of the stack before, or after, their removal therefrom is, or may be, applied a coating of adhesive. It will be understood that although the wrappers, as shown, are one piece 75 wrappers that a composite wrapper, for ex- 80 85 90 95 100

ample, of the type described and claimed in U. S. Letters Patent 1,265,273, granted to myself and another on May 7, 1918, may be utilized.

5 At the wrapping station, while the adhesive coatings on the tabs T and the wrapper W are still fluid or unset, the side panels s' of the wrapper W are wiped preferably simultaneously, into engagement with the corresponding walls of the shaped box and with 10 wrapper-engaging faces of the tabs T. The end flaps f of the wrapper are then wiped into contact with the end walls e of the box and with the remainder of the wrapper-engaging 15 faces of the tabs T, (Fig. 7) and thereafter the end panels e' of the wrapper are folded into adhesive engagement with the end walls of the shaped box (Fig. 8).

The wrapping operation is completed as is 20 well understood in the art, by bending the portions of the wrapper projecting beyond the edges of the box inwardly over the edges of the box and into engagement with the inner surface thereof. During this step, the upper 25 ends of the tabs, as viewed in Fig. 8, which are still soft and pliable because of the wet adhesive coating thereon, are folded over the upper edges of the box at the corners without any tendency to rupture the wrapper at 30 these points.

The box blanks B instead of being shaped into box-simulating position, as in Fig. 3 and thereafter wrapped may be simultaneously bent into box-forming position and wrapped 35 by effecting registering relation between the tabbed blank in the substantially flat or slightly bent position of Fig. 2 and a coated wrapper. During the wrapping operation the side panels s' of the wrapper engage the respective panels s of the box blank and are moved therewith to a position determined by 40 a form block structure F whose outer dimensions correspond to the inner dimensions of the completed box. The end flaps f of the 45 wrapper are then wiped into engagement with the end walls of the box which are held in position against the form block structure. Wrapping of the box is completed in substantially the manner above described.

50 While any or all of the operations above mentioned may be performed manually, it is desirable and practical to perform them by suitable mechanism, for example, the wrappers W may be removed from the stack 55 by the sheet feeding and adhesive coating unit of Nitsch & Federwitz U. S. Letters Patent 1,472,614. Federwitz and Bailey application Serial No. 40,769, filed July 1, 1925, Nitsch & Weightman application Serial No. 69,249, filed November 16, 1925, Federwitz & Bailey application Serial No. 244,124, filed January 3, 1928, or Rider application Serial No. 299,215, filed August 13, 1928; and the coated wrappers transported to a wrapping 60 station by a conveyor of the type disclosed 65

in the aforesaid Federwitz and Bailey application Serial No. 40,769, Federwitz and Bailey application Serial No. 70,462, filed November 21, 1925 or the aforesaid Rider application Serial No. 299,215; the coated 70 wrappers may be applied to the box blanks held in box-forming position by an operator by the wrapping unit disclosed in U. S. Letters Patent to Smith 691,829, Nitsch and Federwitz No. 1,540,900, or to the unshaped 75 blank by mechanism generally of the character disclosed and described in aforesaid Federwitz and Bailey application Serial No. 40,769 or Stokes application Serial No. 147,- 80 405 filed November 19, 1926; and the boxes or box blanks may be fed in succession into the path of the form block structure of the wrapping machine by apparatus generally similar to that described in the aforesaid Federwitz and Bailey application No. 40,769. 85

In lieu of, or in addition to the tabs T, there may be applied to the box blanks B, as indicated in Fig. 10, the tab structures T₁ which extend along and preferably beyond the line of joinder of the side panels s and the bottom panel b ultimately to reinforce the bottom side edges of the box, and also when the tab is of sufficient length as shown, to strengthen the lower corners of the box at the junction of the end, side and bottom walls 95 thereof. Before setting of the adhesive on the tabs, the tabbed blank is moved to a wrapping station at which a wrapper is applied thereto as above described.

Another modified form of tabbed blank 100 is shown in Fig. 11, in which the tabs T₂ extend along and preferably beyond the line of joinder between the end panels e and the bottom panel b of the blank, ultimately to reinforce the bottom, end edges of the box, 105 and also when the tabs extend entirely across the blank, as shown, also to reinforce the vertical corners of the completed box.

In some instances, in which it is not necessary or desirable, that the boxes be as 110 elaborately reinforced as above described, the tabbed blank of Fig. 12 may be utilized. In this modification, the tabs T₂ are relatively short and are preferably disposed intermediate the width of the side panels s 115 at the ends thereof. As in each of the preceding modifications of my invention, before material drying of the adhesive on the tabs, a wrapper is applied to the tabbed blank to produce a wrapped box.

120 It is apparent that a box cover may be similarly formed and to avoid needless repetition the term "bottom" will be understood to include top.

The term "box structure" appearing in the 125 appended claims is used in a generic sense and comprehends both stayed and unstayed boxes.

What I claim is:

1. The method of producing a stayed box 130

which comprises adhesively securing tabs to box structure, and substantially immediately thereafter and before material setting of the adhesive, applying an individual wrapper to 5 the box structure.

2. The method of producing a stayed box which comprises adhesively securing tabs to an unshaped box, substantially immediately thereafter and before material setting of the 10 adhesive, applying a wrapper to the unshaped box, and simultaneously wrapping and shaping the unshaped box to form a wrapped, stayed box.

3. The method of producing a stayed box 15 which comprises coating tabs with adhesive, applying the coated tabs to box structure, substantially immediately thereafter, while the adhesive coatings on the tabs are unset, applying an individual wrapper to the box 20 structure.

4. The method which comprises coating tabs with adhesive, applying the coated tabs to an unstayed box, and substantially immediately thereafter, while the adhesive coatings 25 on the tabs are unset, applying a wrapper to the unstayed box.

5. The method which comprises coating tabs with adhesive, applying the coated tabs to an unstayed box blank, substantially immediately thereafter, while the adhesive coatings 30 on the tabs are unset, applying a wrapper to the unstayed box, and simultaneously wrapping and staying the unstayed box to form a wrapped, stayed box.

6. The method which comprises coating tabs with adhesive, applying the coated tabs to an unshaped box, substantially immediately thereafter and before setting of the adhesive coating on the tabs, applying an 35 adhesive coated wrapper to the unshaped box, and simultaneously wrapping and shaping the unstayed box before setting of any of the adhesive coatings to produce a wrapped, stayed box.

7. The method of producing a stayed box 45 which comprises adhesively securing tabs to a corner-cut box blank, substantially immediately thereafter and before setting of the adhesive, applying a wrapper to the box blank, shaping the blank to form a box, and substantially simultaneously folding the tabs and wrapper to complete the wrapping and staying.

8. The method of producing a stayed box 55 which comprises adhesively securing tabs to a corner-cut box-blank, substantially immediately thereafter applying a corner-cut wrapper thereto, shaping the blank to form a box, and substantially simultaneously folding the tabs and wrapper to complete the wrapping and staying.

9. The method of producing a stayed box 60 which comprises effecting adhesive engagement between walls of an unshaped box and tabs, substantially immediately thereafter,

during a shaping operation, effecting adhesive engagement between other walls of the box and the tabs, and while the adhesive on said tabs is moist, applying a wrapper to 70 walls of the box and to said tabs.

10. The method of producing a stayed box which comprises applying a coating of adhesive to tabs, effecting adhesive engagement between walls of an unshaped box and the 75 coated tabs, substantially immediately thereafter, during a shaping operation, effecting adhesive engagement between other walls of the box and the coated tabs, and applying an adhesive-coated wrapper to tabbed walls of the box before setting of any of the adhesive 80 upon the tabs and wrapper.

11. The method of producing a stayed box which comprises adhesively securing tabs to box structure, transporting the tabbed box 85 structure to a wrapping station, effecting registering relation between the tabbed box structure and a wrapper, and wrapping the box structure before material setting of the adhesive on the tabs.

12. The method of producing a stayed box 90 which comprises adhesively securing tabs to box structure, transporting the tabbed box structure to a wrapping station, effecting registering relation between the tabbed box structure and an adhesive-coated wrapper, 95 and wrapping the box structure before material setting of the adhesive on the tabs and wrapper.

13. The method which comprises adhesively securing tabs to an unshaped box, transporting the tabbed, unshaped box to a wrapping station, effecting registering relation between the tabbed unshaped box and a wrapper, and simultaneously shaping and wrapping the unshaped box before material setting 100 of the adhesive on the tabs to produce a wrapped, stayed box.

14. The method of producing a stayed box which comprises adhesively securing tabs to the wrapper-engaging surface of the box 110 with portions extending beyond edges thereof, substantially immediately thereafter, bending the projecting tab portions over the edges of the box into adhesive engagement with the inner surface thereof, and effecting adhesive engagement between a wrapper and 115 the box, before setting of the adhesive and before said bending of the projecting tab portions.

15. The continuous method of producing 120 stayed boxes which comprises adhesively securing tabs to box structures in succession, substantially immediately transporting the tabbed box structures in succession to a wrapping station, transporting wrappers in succession to a wrapping station, and applying the wrappers to tabbed box structures at the wrapping station before material setting of the adhesive on the tabs.

16. The method of producing stayed boxes 125

- which comprises adhesively securing tabs to box structures in succession, substantially immediately transporting the tabbed boxes in succession to a wrapping station, applying a coating of adhesive to wrappers in succession, transporting the coated wrappers in succession, and applying the coated wrappers to the tabbed box structures at the wrapping station before material setting of the adhesive on the tabs and wrappers. 70
- 10 17. The method of producing stayed boxes which comprises adhesively securing tabs to box structures, substantially immediately transporting wrappers in succession to a wrapping station, and, at the wrapping station, applying the wrappers in succession to tabbed box structures before material setting of adhesive on the tabs. 75
- 15 18. The method which comprises adhesively securing tabs to unshaped boxes, transporting wrappers in succession to a wrapping station, and, at the wrapping station, applying the coated wrappers in succession to unshaped tabbed blanks before setting of any of the adhesive, and simultaneously wrapping and shaping said blanks to form wrapped, stayed boxes. 80
- 20 19. The method of producing a stayed box which comprises coating tabs with adhesive, applying the coated tabs to a box blank, shaping the blank to form a box, and substantially immediately after application of the tabs and before or after shaping of the blanks applying an adhesively-coated wrapper. 85
- 25 20. The method of producing a stayed box which comprises adhesively securing tabs to the wrapper-engaging surface of the box with portions extending beyond the edges thereof, substantially immediately thereafter applying an adhesively-coated wrapper to the box with portions projecting beyond the edges thereof, and before setting of the adhesive on the tabs and wrapper simultaneously folding the projecting portions of the tabs and wrapper over said edges of the box into adhesive engagement with the inside thereof. 90
- 30 21. The method of producing a stayed box which comprises adhesively securing tabs to the wrapper-engaging surface of a box blank, to project in part beyond the edges thereof, substantially immediately thereafter the steps of applying an adhesively-coated wrapper to the blank, shaping, wrapping and staying the box, and simultaneously folding the projecting portions of the tabs and projecting portions of the wrapper into adhesive engagement with the inside of the shaped box. 95
- 35 22. The method of producing a stayed box which comprises applying a pair of adhesively-coated tabs across opposite ends of a box-blank portion adapted to form the box bottom and a pair of opposite side walls with portions of the tabs projecting beyond the edges of the 100
- 40 110
- 45 115
- 50 120
- 55 125
- 60 130

JOHN S. STOKES.
